UNITED STATES PATENT OFFICE.

ALBIN H. WARTH, OF BALTIMORE, MARYLAND, ASSIGNOR TO THE CROWN CORK AND SEAL COMPANY OF BALTIMORE CITY, OF BALTIMORE, MARYLAND, A CORPORATION OF MARYLAND.

CLOSURE FOR BOTTLES AND THE LIKE.

Application filed September 6, 1924. Serial No. 736,215.

This invention relates to closures for bottles and the like and particularly to closures of the crown cork type.

The well known crown cork is a bottle closure comprising a metal shell or crown having a corrugated skirt within which is a sealing disk. The closure is applied to the mouth of a bottle with considerable pressure to effect a seal and the skirt of the crown is crimped about the bottle mouth to secure the crown in place.

In bottling liquids under pressure, such as sodas, beers and the like, and in packaging foods and the like under vacuum, a thorough sealing action is required in order to hold the plus or minus pressure. This can ordinarily be obtained by the use of high grade cork disks, that is, disks devoid of holes or cracks. In the production of cork disks, however, either of natural or composition cork, there is a considerable percentage of low grade disks, unsuitable for the uses referred to. Further, in packaging certain liquids and food products it is undesirable to have the contents come into contact with cork. To protect the contents of the receptacle from the cork of the closure it has been proposed to face the cork disks with a protecting covering. Crowns are known comprising the usual shell, a cork sealing disk and a facing of parchment, varnished paper or the like. Such closures however, do not meet the sealing requirements in the uses above referred to as the facings are almost devoid of elasticity. Even with the cork backing the elasticity has been found insufficient to effect proper sealing in packaging liquids under relatively high pressure or vacuum. Moreover, these facings are apt to tear.

It is the principal object of the present invention to provide a closure of the crown type such that the packaged material is not exposed to cork; such that a proper seal for liquids and the like under relatively high pressure or vacuum can be effected; and such that the low grade cork disks may be utilized in making the closure.

With this general object in view the invention consists in the closure which will first be described in connection with the accompanying drawing and then more particularly pointed out.

The drawing shows in enlarged cross sec-

tion, a closure constructed in accordance with the invention.

Referring to the drawing which illustrates one embodiment of the invention, the closure shown comprises a metal shell or crown 11. This shell has the usual corrugated skirt 12 for securing the closure to a receptacle, such as a bottle. Within the skirt, and engaging the inner wall of the crown, the closure has a compound sealing disk comprising an inner disk and an outer disk. The inner disk is characterized by a high degree of elasticity. In the embodiment of the invention here illustrated as an example, the inner disk 14 is formed of cork. This may be either natural cork or composition cork, i. e., agglomerated cork granules. The cork is formed into disks in any suitable manner.

The outer disk is characterized by a high degree of elasticity, toughness and impermeability to moisture. In closures embodying the invention to the best advantage the outer disk is also substantially tasteless and odorless. In the present exemplification the outer disk 15 is made of a synthetic material comprising a rubber compound, such as latex, and paper pulp. This material may have various compositions and be prepared in various ways. For example, a convenient material comprises a sheet or web of high porosity formed by a paper-making process and composed of loosely-matted relatively-long fibres each of which is coated with a rubber compound. From this sheet or web the disks are cut in any suitable manner. The compound disk may be assembled in the metal shell in any suitable manner. For example, the inner cork disk may be secured in place by means of a binding agent between the inner face of the disk and the wall of the shell. Likewise, the outer disk may be secured to the inner disk by a binding agent either before or after the inner disk is assembled. Suitable binding agents are known in the closure art and no further description is here necessary.

If desired, the outer disk 15 may have a protective coating of a character to improve its appearance and to increase its impermeability to the action of the acidulous and alkaline liquids. This coating may be a wax, cellulose vegetable oil, or varnish-like product, combined or uncombined with pig-

ment. If a pigment is used it should preferably be inert, insoluble in water and not readily attacked by organic or mineral acids. An example of such a pigment is titanox, a mixture of barium sulphate and titanium oxide. Such a coating serves to protect the disk from the bottled liquid and to protect the liquid from the disk.

The coating described is relatively thin and is not illustrated but it will be clear that if a coating is used, it is applied in any suitable manner, to the outer face of the outer disk 15.

Instead of the coating described, paraffin or other mineral or vegetable wax may be sweated into the pores of the outer disk. To such wax may be added aluminum stearate or the equivalent to make the wax less porous.

20 The closure described is well adapted to the uses above mentioned. It is capable of giving a proper seal in packaging materials under relatively high pressure or vacuum and at the same time it makes possible the utilization of low grade cork disks. More-

over, in case cork is used for the inner element of the compound disk, the outer disk protects the contents from the cork and consequently the closures can be used in cases where even high grade natural cork is undesirable.

The term "bottle" is used in specification and claims in a comprehensive sense to include all like receptacles.

What is claimed is:

1. A closure for bottles and the like, comprising a metal shell and a compound sealing disk comprising an inner cork element and an outer element formed by a paper-making process and composed of loosely-
40 matted relatively-long fibres each of which is coated with a rubber compound.

2. A closure for bottles and the like, comprising a metal shell and a disk for sealing engagement with the bottle mouth and formed of a synthetic composition of latex and paper pulp.

In testimony whereof, I have hereunto set my hand.

ALBIN H. WARTH.
